UNITED STATES PATENT OFFICE.

FRANCIS B. BADT, OF CHICAGO, ILLINOIS.

ELECTRIC-ARC LAMP.

SPECIFICATION forming part of Letters Patent No. 681,179, dated August 27, 1901.

Application filed February 25, 1901. Serial No. 48,732. (No model.)

To all whom it may concern:

Be it known that I, FRANCIS B. BADT, a citizen of the United States, residing at Chicago, in the county of Cook and State of Illinois, 5 have invented a certain new and useful Improvement in Arc-Lamps, (Case No. 1.), of which the following is a full, clear, concise, and exact description, reference being had to the accompanying drawings, forming a part 10 of this specification.

My invention relates to arc-lamps, and has for its object the provision of an improved support for the globe that may be adaptable to any form of arc-lamp, and, second, the 15 provision of an improved yielding clamping device for that supplemental globe or casing used in inclosed-arc lamps that is usually inclosed within a second globe, whereby the supplemental arc-inclosing globe may be 20 readily placed in position, while through the agency of the improved support it is also adapted to be unseated to permit of the escape of accumulated gas.

The mechanism of the lamp, as is well 25 known, is usually contained within a casing located above the carbons, while the main outer globe is suspended in some way by mechanism that permits the globe to be elevated about the carbons or be lowered away from 30 the carbons when the lamp is to be trimmed or for other purpose. Heretofore rather unsatisfactory mechanism has been employed for this purpose. For inclosed-arc lamps chains have been employed to suspend the 35 outer globe and to secure its adjustment relative to the carbons. This feature of my invention may be said to comprise positive globe-retaining means in the form, preferably, of rods that are movable relatively to each 40 other longitudinally, which rods are diametrically disposed with respect to the globe and preferably extend within the casing containing the lamp-operating mechanism. One of each pair of the relatively movable or telescoping rods is secured to the globe, while 45 the other serves when the globe is being lowered to engage some portion fixed with respect to the mechanism-casing, so that as the globe is lowered both members of each pair 50 of rods are adapted to move downwardly, whereby the globe may be lowered to a much

greater extent than the height of the mechanism-casing.

The improved clamp of my invention for supporting the inner arc-inclosing globe or 55 casing is preferably in the form of a bifurcated spring clamping member that is best formed from strip spring metal, which clamping member is anchored at its intermediate portion to the gas-cap. This bifurcated 60 clamping member projects, preferably, slightly beyond the diameter of the inner globe, and consequently when in place tends to thrust the globe to one side, and to prevent the globe from becoming dislodged I provide a nose 65 located diametrically opposite to the point of attachment of the clamping-spring to the gas-cap that engages the upper flanged portion of the inner globe and prevents its displacement. 70

I will explain my invention more fully by reference to the accompanying drawings, in which—

Figure 1 is a sectional elevation of the mechanism-casing, the globe, and globe-suspending means, other features of the lamp being omitted for the sake of clearness, as these are well understood by those skilled in the art. Fig. 2 is a detail of a structural feature entering into the mechanism illustrated 80 in Fig. 1. Fig. 3 is a sectional view showing the mechanism constructed in accordance with my invention for holding the inner globe in place. Fig. 4 is a sectional plan view on line 4 4 of Fig. 3. Fig. 5 is a detail view of 85 another means of supporting the clamp. Fig. 6 is a view on line 6 6 of Fig. 5.

Like parts are indicated by similar characters throughout the different figures.

The mechanism of the lamp need not be 90 illustrated, as the particular form of lamp does not constitute part of my present invention, and any of the well-known forms which are familiar to those skilled in the art may be used.

The casing *a* is designed to contain the operating mechanism. This casing is preferably provided with a downwardly-extending apron *b*, which serves as a shield for the outer globe *c*. The globe *c* is preferably provided 100 with a groove *d* at its neck, with which a ring *e* may be engaged through the agency of

screws *f f*, distributed around the ring at suitable intervals. The ring *e* is provided at diametrically opposite points with vertical passages passing through the same, which are 5 cupped at their lower portions to receive the globular ends *g g* of extension- rods *h h*. These extension- rods are component parts of globe-supporting means, into which supporting means also enter the additional extension- rods *i i*, that are preferably tubular and through which preferably the extension- rods *h h* are adapted to move. The upper ends of the extension- rods *h h* are enlarged and are limited in their downward movement 10 with respect to the rods *i i* by having these enlargements engage corresponding and co-acting enlargements provided upon the tubes *i i*. The tubes *i i* are preferably closed and capped at their upper ends. 15 When the globe of the lamp is elevated and is to be clamped in position, retaining devices are employed, which are preferably in the form of enlargements *k k*, fixed with relation to the rods *h h* and placed adjacent to the 20 ring *e*, which enlargements *k k* are provided with recesses *l l*, that are adapted to engage any suitable form of stops, which are preferably in the form of thumb-screws *m m* to secure their positive action. When the outer 25 globe is to be lowered, the thumb-screws are loosened, whereupon the globe of its own weight may be permitted to descend. Owing to the telescopic arrangement of the rods *h h* and *i i*, the outer globe may be lowered sufficiently to permit access to the carbons of 30 the lamp. As the globe is lowered the lower ends of the rods *i i* come in contact with the floor of the mechanism-casing, thereby limiting the downward movement of the sections 35 *i i*. The rods *h h*, however, may still continue in their downward movement until the heads upon the upper ends thereof engage the lower ends of the tubes *i i*. The globe- 40 supporting rods are preferably sealed within the mechanism-casing. 45

The inner arc-inclosing globe *n* may be of the construction in which there is a rim or enlarged portion at the upper end thereof and which is entirely closed at the lower 50 end. With the rim the device of the bifurcated spring-clamp *o* of my improved construction is adapted to engage.

The clamp is anchored at its central portion by means of a thumb-screw *p*, that passes 55 through the gas-cap *q*. The hole provided in the central portion of the spring-clamp is somewhat larger than the stem of the thumb-screw *p*, so that when the screw is loosened the spring-clamp may occupy a different angular position with respect thereto than when 60 the clamp is tightened in place. This enlargement may be of oval shape, so as to provide a greater diameter in a radial line from the carbon, as the swinging motion of the 65 bifurcated globe-clamping spring is only required to be in an up-and-down direction. By this arrangement the removal and replace-

ment of the inner globe is facilitated. Owing to the fact that the spring-clamp extends only half-way approximately around the inner globe, I provide a nose *r*, that is located diametrically opposite the point of attachment of the spring-clamp to the gas-cap, which nose effectually prevents the displacement of the inner globe with respect to the carbons and 70 the gas-cap. 75

It is apparent that the clamp of my invention will permit the inner arc-inclosing globe to be momentarily unseated from the gas-cap to permit from time to time the escape of the 80 gas formed in the burning of the lamp.

In Figs. 5 and 6 I have shown a modified form of suspension for the spring-clamp, consisting of a post *s*, suitably anchored in position, to which is pivoted a rod *t*, that carries the spring-clamp at its lower end. The point of pivotal connection is preferably provided with a pivotal clamping-screw *u*, that at once forms the pivot about which the spring-clamp may be rotated and also serves 85 to secure the spring-clamp in the angular position to which it has been adjusted.

In addition to the clamping-screw which is illustrated in Figs. 5 and 6 a spring *v* may be employed, that is adapted for engagement 95 with one cam-surface to maintain the globe-clamping spring in one position of angular adjustment, as illustrated, or this spring may engage the other cam-surface *w*, which may serve to hold the globe-clamping spring in 100 another position of angular adjustment, so that the lamp-trimmer by thrusting the globe-clamping spring in one direction or the other may engage the same with or disengage it from the globe. 105

It is obvious that changes may be made from the embodiment of my invention herein shown and particularly described, and I do not, therefore, wish to be limited to the precise disclosures herein set forth; but,

Having thus set forth my invention, I claim as new and desire to secure by Letters Patent—

1. In an arc-lamp, the combination with a globe therefor, of a ring engaging the upper edge portion of the globe, the said ring being provided with passages extending through the same in a vertical direction, the said passages being cupped at their lower portions, rods *h*, *h* passing through the ring and provided with 115 enlarged ends *g g*, and means whereby the said rods *h h* may be permitted vertical movement and limited in their vertical movement, substantially as described. 120

2. In an arc-lamp, the combination with a 125 globe therefor, of a ring engaging the upper edge portion of the globe, the said ring being provided with passages extending through the same in a vertical direction, the said passages being cupped at their lower portions, rods *h*, *h* passing through the ring and provided with 130 enlarged ends *g g*, rods *i i* having telescopic engagement with the rods *h h*, means whereby the telescoping rods may have their rela-

tive longitudinal movement limited, and means for limiting the downward movement of both pairs of telescoping rods, substantially as described.

5. In an inclosed-arc lamp, the combination with a gas-cap, of an arc-inclosing globe, a bifurcated spring-clamp having its tongues engaging the upper portion of the said globe, and means coacting with the spring-clamp 10 for preventing the lateral displacement of the globe, substantially as described.

4. In an inclosed-arc lamp, the combination with a gas-cap, of an arc-inclosing globe, a bifurcated spring-clamp having its tongues 15 engaging the upper portion of the said globe, and a nose located opposite the spring-clamp for engaging the globe, and in coöperation with the spring-clamp serving to prevent the lateral displacement of the globe, substantially as described.

5. In an inclosed-arc lamp, the combination with a gas-cap, of an arc-inclosing globe, a 20

spring-clamp engaging the arc-inclosing globe to engage the same with the gas-cap, and means for fastening the spring-clamp in position that permits a change in the angular 25 position of the clamp with respect to the globe, substantially as described.

6. In an inclosed-arc lamp, the combination with a gas-cap, of an arc-inclosing globe, a 30 spring-clamp engaging the arc-inclosing globe to engage the same with the gas-cap, a pivotal mounting for the spring-clamp that permits of the angular adjustment of the said clamp with respect to the globe, and means 35 whereby this angular adjustment of the spring-clamp may be preserved, substantially as described.

In witness whereof I hereunto subscribe my name this 23d day of February, A. D. 1901. 40

FRANCIS B. BADT.
